UNITED STATES PATENT OFFICE.

EARL L. CALDWELL AND FRANK FARRIS, OF CENTRALIA, WASHINGTON.

TOY CATAPULT.

Application filed February 6, 1928. Serial No. 252,198.

The invention aims to provide a simple and inexpensive, yet a very desirable catapult for starting wheeled toys devoid of motive power, across a floor, sidewalk or the like, and with this end in view, the invention resides in the novel subject matter hereinafter described and claimed, description being accomplished by reference to the accompanying drawing.

10 Fig. 1 is a perspective view of a catapult constructed in accordance with our invention.

Fig. 2 is a vertical transverse sectional view.

15 Fig. 3 is a fragmentary perspective view showing parts in different positions from Fig. 1.

The drawing above briefly described, illustrates the preferred form of construction, 20 and while this construction will be herein specifically explained, it is to be understood that within the scope of the invention as claimed, variations may be made.

The catapult embodies a rectangular base 25 4 and a plurality of parallel walls secured to and rising from said base, two outer or side walls 5 and several intermediate walls 6, being shown, all of these walls being preferably tied together at their upper rear corners, by an appropriate bar or strip 7. Each of the walls 5-6 is formed with a longitudinal slot 8 which is parallel with the base 4, the walls 5 are provided with rearwardly facing shoulders 9 at the rear 30 ends of their slots, and similar shoulders 10 are formed at the rear ends of the walls 6. The walls 5 project rearwardly beyond the shoulders 9 and are provided with bearing openings 11, and the front portions of 40 these walls are formed with openings 12.

A rod 13 passes through all of the slots 8 and two elastic bands 14 are provided to forwardly shift this rod when desired, said rod being normally engaged with the shoulders 9-10 however as shown in Figs. 1 and 2 and hence held against forward shifting. The elastic bands 14 pass through the openings 12 and pass around the rod 13 at opposite sides of the walls 5.

50 Mounted in the bearing openings 11 is a rock shaft 15 provided with an operating handle 16, the ends of said rock shaft being equipped with forwardly projecting arms 17 adapted to underlie the rod 13 when the latter is engaged with the shoulders 9-10. After setting of the catapult as in Figs. 1

and 2 and placing of the toys upon the base 4, between the walls 5-6, turning of the shaft 15 under the influence of the handle 16, causes the arms 17 to upwardly force the rod 13 from engagement with the shoulders 9-10. Hence, the elastic bands 14 immediately come into play to forward shift said rod, thus projecting the wheeled toys from the base. The front edge of this base is 60 preferably beveled as at 18, to ease the wheeled toys down onto the surface upon which they are to run during the "race" 65 upon which they are started by the catapult.

Preferably, all parts with the exception 70 of the elastic bands 15, are formed of wood and by preference the exact details herein disclosed are followed. However, it will be understood that other materials could be used and that within the scope of the invention as claimed, numerous changes as to form, proportions, designs and minor details, may be made.

We claim:-

1. In a toy catapult, a base, parallel walls 80 secured to and rising from said base, said walls having horizontal slots, a rod extending between said walls and having its ends slidably received in said slots, resilient means for forwardly shifting said rod in 85 said slots, and means for holding said rod against forward movement until desired.

2. In a toy catapult, a base, parallel walls secured to and rising from said base, said walls having horizontal slots and rearwardly 90 facing shoulders at the rear ends of said slots, a rod extending between said side walls and having its ends passed through said slots, and resilient means for forwardly shifting the rod, said rod being engageable with said shoulders to hold it against forward shifting 95 until desired.

3. In a toy catapult, a base, parallel walls secured to and rising from said base, said walls having horizontal slots and rearwardly 100 facing shoulders at the rear ends of said slots, a rod extending between said side walls and having its ends passed through said slots, resilient means for forwardly shifting the rod, said rod being engageable with said shoulders to hold it against such shifting until desired, and a rock shaft extending between and supported by the rear ends of said walls, said rock shaft having a handle and projections for forcing said rod from 110 said shoulders.

4. A toy catapult comprising a base, a

plurality of parallel walls secured to and rising from said base, said walls having longitudinal slots, the two outermost walls being provided with rearwardly facing shoulders at the rear ends of their slots and with aligned bearing openings at their rear ends, a rod passing through said slots and engageable with said shoulders, elastic means connected with the ends of said rod and connected with the front portions of said outermost walls for forwardly shifting the rod when released from said shoulders, and a rock shaft mounted in said bearing openings, said rock shaft having a handle and projections for forcing said rod from said shoulders.

5. In a toy catapult, a wall having a slot and an opening at one end of said slot, a

toy-projecting rod passing slidably through said slot, and an elastic band passing through 20 said opening and passing around said rod at opposite sides of said wall.

6. In a toy catapult, a base, parallel walls secured to and rising from said base, said walls having horizontal slots and openings, 25 a rod extending between said walls and having its ends slidably received in said slots, elastic bands passing through said openings and passing around said rod at opposite sides of said walls, whereby the said rod is 30 forwardly shifted in said slots.

In testimony whereof we have hereunto affixed our signatures.

EARL L. CALDWELL.
FRANK FARRIS.
